Carl H. Crawford ATTORNEY

UNITED STATES PATENT OFFICE.

LOUIS H. WOODCOCK, OF SPOKANE, WASHINGTON.

AUTOMATIC THRESHOLD-SPACE CLOSURE.

Application filed February 9, 1927. Serial No. 166,985.

One of the objects of this invention is to equip hingedly mounted doors with means for closing the space between the bottom edge of the door and the floor when the door is closed so that the usual threshold may be dispensed with.

A further object is to provide a device of this character with means whereby the device is lifted out of contact with or from the floor whenever the door is not in a closed position so as to facilitate and not in any way interfere with free opening and closing movements of the door.

A special feature of the invention is to provide a device of this character which is substantially invisible from either side of the door irrespective of the position of the latter, especially from the line of vision of a person standing or sitting.

A novel phase of the invention resides in the manner of disposing the device with respect to the bottom edge of the door with a view of rendering the device substantially invisible by reason of the fact that the device is only coextensive with the area of the bottom edge of the door, and in some cases even less than such coextensive relation as to size.

A further feature consists in making a device of this character which is wholly automatic in its operation, as a result of movement of the door.

The device of my invention has many other features and advantages which will be more fully described in connection with the accompanying drawing and which will be more particularly pointed out in and by the appended claim.

In the drawing:

Fig. 1, is a view of one side of a hinged door equipped with the device of my invention and showing the door in a closed position.

Fig. 2, is a view of the remaining side of the door showing the same in a closed position.

Fig. 3, is a sectional view on line 3—3 of Fig. 2, on a slightly enlarged scale, showing the position of the parts with the door closed.

Fig. 4, is a view similar to Fig. 3, showing the position of the parts with the door open.

Fig. 5, is a sectional view on line 5—5 of Fig. 2.

Fig. 6, is a sectional view on line 6—6 of Fig. 3.

Like characters of reference designate similar parts throughout the different figures of the drawing.

It is immaterial whether the device of my invention is applied to an outside or an inside door as it will function with equal efficiency on either, and in the following description I will designate each side of the door by a separate reference character to facilitate an explanation of the invention and without reference to the disposition of the door with respect to outside or inside.

An ordinary form of door is indicated at 1 and the letter A, designates one side thereof while the letter B designates the other side thereof. Said door is hinged, at 2, to swing in a door frame, the hinge side being indicated at 3 and the jam side being indicated at 4. As the particular construction of the door and frame are not essential to my invention, no further detail description thereof is necessary.

The lower edge 5, of the door 1, is in free clearance from the floor 6 for a distance approximately equal to the height of the usual threshold, although in some cases more or less clearance may be provided. However, it is an advantage of my invention that the door of the usual stock size need not be modified by being shortened, in order that the device of my invention may be applied thereto. It is a feature of my invention to entirely dispense with the threshold, which omission alone, affords ample clearance for the installation of my device, and it is also to be noted that the floor adjacent to the door is not cut away or in any manner altered in order to accommodate my invention. Thus, a carpet or rug may extend beneath the door without in any way interfering with the operation of my invention.

Reverting now to a further description of the structure, a closure, preferably but not

necessarily in the form of a weather strip 7, is suitably disposed abreast of the lower edge 5, and is substantially coextensive therewith. In the form shown, one side edge 8, 5 of said strip is hingedly connected by means such as staples 9, to the bottom of the door near the face A, of the latter, leaving the remainder, or the remaining side of the strip 7, free. I preferably hinge the bight portion 10 of the strip so that the rubber portion 10, will be effective for engagement against the floor. The disposition is such that the free or rubber side edge of the strip 7 will extend toward the side B, of the door. I 15 have shown the strip 7 composed of a sheet metal body bent double, and an interposed length of rubber secured between the doubled portions by means such as rivets 11, although this is not an essential construction.

One member of an operating mechanism for the strip is secured to the latter, which I will next describe in detail.

Said operating member has a portion 12 that is disposed in the strip 7, as shown in Fig. 5, and I provide the same with offset portions 13 to prevent rotation of said member in said strip. Thus, when the rivets 11 are in place, said portion 12, is securely held in place. Said portion 12, has an arm 14 which extends outwardly from the strip and is provided with a bent end 15 which extends substantially parallel with said strip, the entire projecting portion being hereinafter referred to as an operating arm.

I will next describe the remaining portion of the operating mechanism which is shown mounted upon the door.

The door portion of said operating mechanism is shown as including a casing having a back wall 16, secured to the B-side of the door 1, by means such as screws 17. Said casing may have a top wall 18, end walls 19 and 20, and an outer wall 21, that may be removable, the bottom being open, as shown. An operating or plunger rod 22 is slidably mounted in the walls 19 and 20 and is provided with a collar 23 which is suitably fixed thereon and which performs the function of a spring abutment. An expansively acting spring 24, is interposed between wall 20 and said collar 23 and normally urges the rod 22, to the left of Fig. 6. On an adjacent part of the door frame, as indicated at 25, I may provide a metal abutment plate against which said rod 22 may engage when the door is closed, to shift rod 22 to the right of Fig. 6, against the action of spring 24, the purpose of which will presently appear.

Means is provided for tilting said strip upwardly or downwardly, responsively to the action of rod 22, which I will next describe in detail.

I have shown a lazy-tong structure or device for performing the function of impar-

ing movement to the strip as a result of actuation of rod 22. One element 26, thereof is pivoted at its upper end to collar 23, at 27, and is pivoted at its remaining end at 28, to element 29, the latter being pivoted at 30, to a sleeve 31, on arm 15. Element 32, is pivoted at 33, to the casing and is pivoted at 34, to element 26, and at its lower end it is pivotally connected at 35, to element 36. Element 36, is pivoted to sleeve 31, at 30.

The operation is as follows;

When the door is opened and the rod 22 is moved away from abutment 25 and thereby freed, it is instantly actuated by spring 24 and moved to the left of Fig. 6, until the collar 23 engages wall 19. This retracts the lazy-tong device and tilts the strip 7 from the projected position shown in Fig. 3, to the retracted position shown in Fig. 4, so that the strip abuts in flat engagement against the lower edge 5, of the door 1. This renders the strip 7 even less visible than when the same is projected. It also insures that there will be no interference or resistance with the floor 6, or any rug or carpet thereon, against opening or closing movement of the door.

When the door is closed, as shown in Figs. 2 and 3, the rod 22 engages abutment 25, and is shifted into the position shown in Fig. 6, thereby expanding the lazy-tong device and tilting the free edge of strip 7 downwardly against the floor or any covering thereon. By reason of the fact that the free edge of strip 7 is formed of rubber, I can readily compensate for any unevenness of the floor or any defect of alignment and insure a close engagement with the floor amounting to a tight closure. By reason of the relatively loose pivotal connections with the lazy-tong device, the latter can slightly shift its position in the performance of its retractive and expanding movements especially in view of the slight movement and the light duty which it is called upon to perform.

It is believed that the device of my invention will be fully understood from the foregoing description, and while I have herein shown and described one specific form of my invention, I do not wish to be limited thereto except for such limitations as the claim may impart.

I claim:

The combination with a door frame, of a door hinged to swing in said frame and having a bottom edge in free clearance from the floor, a weather closure strip having one side edge thereof hinged to said bottom edge of said door near one side of the latter, an operating member having one portion anchored in said strip and provided with an arm projecting therefrom at the free edge of said strip, a lazy-tong pivoted to said arm and

pivoted to said door, a plunger rod slidably mounted on said door and adapted for engagement with said frame to actuate said rod when the door is closed, said rod being 5 operatively connected with said lazy-tong to contract the latter and lift said strip when said door is opened, a spring for actuating

said rod to lift said strip, said rod extending said lazy-tong when in coaction with said frame to extend said lazy-tong and lower 10 said strip into engagement with the floor.

In witness that I claim the foregoing as my own, I hereby affix my signature.

LOUIS H. WOODCOCK.
